(57) **CLAIM**

The ornamental design for a motorcycle pushrod arch, as shown and described.

DESCRIPTION

FIG. 1 is a bottom, front left perspective view of a motorcycle pushrod arch according to my invention.

FIG. 2 is an enlarged bottom, front left perspective view of the motorcycle pushrod arch of FIG. 1.

FIG. 3 is an enlarged top, rear right perspective view of the motorcycle pushrod arch of FIG. 1.

FIG. 4 is a front, elevation view of the motorcycle pushrod arch.

FIG. 5 is a top plan view of the motorcycle pushrod arch.

FIG. 6 is a rear, elevation view of the motorcycle pushrod arch.

FIG. 7 is a right side, elevation view of the motorcycle pushrod arch, the left side, elevation view being a mirror image thereof; and,

FIG. 8 is a bottom plan view of the motorcycle pushrod arch. The broken lines shown in FIG. 1 are for illustrative purposes only and form no part of the claimed design.
